UNITED STATES PATENT OFFICE.

JOHN F. KELLY, OF TRENTON, NEW JERSEY, ASSIGNOR TO THOMAS MADDOCK'S SONS COMPANY, OF TRENTON, NEW JERSEY, A CORPORATION OF NEW JERSEY.

SEAT-OPERATED WATER-CLOSET.

1,237,911.

Specification of Letters Patent. Patented Aug. 21, 1917.

Application filed June 8, 1915. Serial No. 32,804.

To all whom it may concern:

Be it known that I, JOHN F. KELLY, a citizen of the United States, and a resident of Trenton, in the county of Mercer and State 5 of New Jersey, have invented certain new and useful Improvements in Seat-Operated Water-Closets, of which the following is a specification.

My present invention relates to the construction of water closets particularly that 10 type wherein the flushing of the bowl is automatically controlled by the movement of the seat.

The object of the invention is to simplify 15 and improve the construction of closets of this type as heretofore proposed so that a more sanitary closet is attained. To this end by practising this invention it is possible to maintain a continuous flushing rim or spray 20 of flushing water all around the bowl thus insuring that all parts of the bowl will be effectively cleansed. Other objects and advantages of the invention will appear from the subjoined description.

25 The invention consists in the improved construction of water closet hereinafter more particularly described and then specified in the claims.

In the accompanying drawings, Figure 1 30 is a vertical cross-section through a water closet bowl and seat therefor constructed in accordance with this invention.

Fig. 2 is a plan view of the same.

Fig. 3 is an enlarged cross-section through 35 a form of flushing valve which may be employed and illustrating part of the closet in section, the section being taken on the line 3—3 Fig. 2.

Fig. 4 is a vertical cross-section through 40 another type of bowl to which my invention is applied.

Fig. 5 is a plan view of the same.

Fig. 6 is a section through the casing for 45 the valve outlet taken on the line 5—5 Fig. 5 and illustrates the valve in side elevation.

In the drawings 1 indicates the bowl proper supported on a pedestal 2 and 3 indicates the flushing rim located entirely around the upper edge of the bowl 1. The 50 bowl may be of any desired type, that illustrated being of the well-known siphon-jet class provided with a chamber 4 from which water passes to the flushing rim 3 direct and to the siphon-jet 5 in the usual and well understood manner. The particular type of

bowl to which my invention is applied is immaterial and further detailed description of the same is deemed unnecessary.

6 indicates a casing preferably integral with the bowl 1 and rising from the rear part thereof above the chamber 4. The casing 6 houses the discharge outlet 7 of a flushing valve 8 and communicates by a passage 9 with the chamber 4. The flushing valve 8 is disposed preferably bodily in a plane above the flushing rim 3 and is provided with a valve stem 10 which protrudes forwardly from the casing 6. The discharge outlet 7 of the valve is packed in a watertight manner in the casing 6 and by preference the main body of the valve extends backward from the casing and is provided with an inlet end 11 which connects with the source of water supply and an alternate inlet and outlet end 12 connecting with a tank 70 for holding the body of flushing water and which determines the volume of water that flushes the bowl at each operation.

The upward integral extension 6 is preferably provided with a forwardly protruding ledge or projection 30 extending from the top of the extension toward the front of the bowl and overhanging the valve stem 10 so as to cover or partially conceal the coupling connections 31.

85 13 indicates the seat pivotally secured to the casing 6 by shaft or pintle 14 and arms 15. The shaft 14 is by preference located in the projecting ledge 30 so that the point of pivotal movement of the seat is brought forward toward the end of the valve stem 10. By so pivotally mounting the seat the usual separate posts secured to and rising from the bowl are avoided thus overcoming expensive fittings and the annoyance of the posts becoming loose and shaky. The rear end of the seat 13 is in line with and engages the exposed projecting end of the valve stem 10 to actuate the valve. The normal position of the seat when the closet is not in use is as 90 shown in Fig. 1 with the forward end tilted upward. In this position the tank is empty, the water having automatically flushed the bowl as soon as the seat 13 was free to rise. Upon depressing the seat the water is shut 105 off from the bowl and communication is established from the source of supply to the tank which fills so that as soon as the seat is released the water from the supply to the tank is shut off and communication is es- 110

tablished between the tank and the bowl, thus flushing the latter.

Any desired suitable type of flushing valve may be employed, the one illustrated comprising a valve disk 16 controlling the communication between the tank and the bowl 1 and a valve disk 17 controlling the communication between the source of supply and the tank. The disk 16 is secured 10 to the valve stem 10 and coöperates with its seat 18 while the disk 17 is secured to an extension 19 of the valve stem 10, there being preferably a slight lost motion between the valve stem and its extension to insure proper seating of the valve disk 16. The disk 17 coöperates with its seat 20 to close communication between the source of supply and the tank.

When the seat 13 is depressed the valve stem is forced inward and the valve disk 16 engages its seat 18 and shuts off communication between the tank and the bowl 1. By the same operation the valve disk 17 is forced away from its seat and water passes 25 from the source of supply to the tank. When the seat is released the spring 21 automatically raises it and draws the valve disk 16 away from its seat and the water previously filled into the tank passes into the bowl 30 through passages 22, discharge outlet 7, passage 9 and chamber 4 and flushes the same until the tank is empty. At the same time the spring 23 seats the valve disk 17 and closes communication between the source of supply and the tank.

With reference to the construction illustrated in Figs. 4, 5 and 6, the capability of the invention for application to a bowl having a raised vent 25 above the rim is shown. 40 In this case the casing 6 which houses the discharge outlet of the valve 8 is disposed at one side of the raised vent while in other respects the construction and operation is the same as previously described with the 45 exception that in order to make room for the raised vent the seat 13 is divided at the rear and one arm of it engages the valve stem 10.

It will be understood that the construction shown and described is for illustration 50 purposes only and not intended as limiting the invention except as may be specified in the appended claims.

Copies of this patent may be obtained for five cents each, by addressing the "Commissioner of Patents, Washington, D. C."

What I claim as my invention is:—

1. A water closet comprising a bowl, a flushing rim, a raised vent hood the entrance 55 to which overhangs the bowl forward of the rim at the rear of the bowl, a casing forming a continuation of said hood at one side thereof, a flushing valve housed in said casing and having a valve stem projecting forwardly through said casing, a seat adapted to engage the projecting end of the valve stem and a pintle to which said seat is pivoted, said pintle being disposed in the upper wall of said casing and hood whereby an 65 unobstructed passage through the vent is obtained.

2. A water closet comprising a bowl, a flushing rim entirely surrounding said bowl, a raised vent hood the entrance to which 70 overhangs the bowl forward of the rim at the rear of the bowl, a hollow casing forming a continuation of said hood at one side thereof, a flushing valve the discharge of which is housed in said casing and provided 75 with a valve stem projecting forwardly through said casing, a seat straddling said vent hood at the rear and adapted to engage the projecting valve stem, the upper wall of said hood and casing being provided with 80 a thickened portion to which the seat is hinged thereby leaving an unobstructed passage through the vent.

3. A water closet having a bowl provided with an upwardly extending integral casing 85 at the rear side thereof and above the upper edge, said casing being provided with a forwardly projecting overhanging ledge, a seat pivoted directly to said ledge, a valve 90 to control the flushing of the bowl the outlet of which is located in said casing and a valve stem projecting forward from said casing beneath said ledge, the exposed end of said stem being adapted to be operated by said seat whereby the position of the valve 95 is determined by the position of the seat.

Signed at Trenton, in the county of Mercer and State of New Jersey, this third day of June, A. D. 1915.

JOHN F. KELLY.
